UNITED STATES PATENT OFFICE

RICHARD NORMAN BOOTH, OF LONDON, ENGLAND, ASSIGNOR TO "SOCIETE ANONYME POUR L'EXPLOITATION DES PAPETERIES L. LACROIX FILS," OF ANGOULEME (CHARENTE), FRANCE, A CORPORATION OF FRANCE

HAND OPERATED CIGARETTE MAKING MACHINE

Application filed May 23, 1932, Serial No. 613,059, and in Great Britain March 8, 1932.

This invention relates to hand-operated cigarette-making machines of the kind employing an endless apron passing around two rollers mounted one in each of the halves of a hinged frame or book like casing, the cigarette being formed in the sagging portion or trough of the endless apron, when such apron is given a to and fro movement around the rollers.

10 In this kind of machine, when the frame is opened or unclosed (like a partly open book), the lateral edges of the endless apron are exposed so that the charge of tobacco cannot be spread evenly in correct form in the trough in the upper run of the apron and especially at the ends of the trough; the tobacco is in fact liable to fall out from the open ends of the apron trough and to interfere with the shutting or closing of the frame or book.

15 Moreover, it is subsequently necessary to cut or trim the ends of the roll of tobacco formed in the apron-trough after the cigarette paper has in turn been rolled around the charge.

20 Further, it has sometimes been found that the endless apron is damaged if the halves of the frame or casing are opened out to too great an extent.

According to the present invention, I provide, in a hand-operated machine with endless apron and of the above mentioned kind, two cover plates or cheek-plates, one at each end of the hinged or pivoted frame or book-like casing, these cover plates being mounted 35 in such a way that they are substantially at right angles to the hinge-axis of the frame or casing and that the cover plates remain in position, adjacent to the lateral edges of the endless apron, whether the frame be 40 closed or open. When the frame or casing is opened out to expose the trough in the endless apron between the rollers, these cover plates or cheek-plates still protect, or act as 45 closures for, the extremities of the trough in the apron, so that during the rolling operation, the ends of the roll of tobacco in the trough can, if necessary, make contact with these flat cover plates. The cover plates also 50 prevent the charge of tobacco from escaping

over the lateral edges of the apron adjacent to the ends of the trough when the charge is being inserted or rolled or withdrawn.

By means of these cover plates I can also limit the outward movement of the rollers 55 when the casing is being opened, and likewise prevent the rollers from pressing one against the other when the casing is closed up.

The invention is hereafter described with reference to the accompanying drawing, in 60 which:—Fig. 1 is an end elevation of the machine with the hinged halves of the frame in the opened position. Fig. 2 is a similar view showing the hinged halves in the closed position. Fig. 3 is a plan of Fig. 1 while 65 Fig. 4 is a side view of the machine. Fig. 5 shows this form of the cover plate detached. Fig. 6 is an end view similar to Fig. 2, but showing a modified form of cover plate. Fig. 7 is a plan view of a machine according to 70 Fig. 6.

The frame of the machine is shown of rectangular shape and formed of halves or members *a* *b* hinged together at *c*. The member *a* is provided with a roller *d* having a 75 spindle *d*¹ journaled in the end walls *a*¹ *a*¹, and the member *b* is provided with a roller *e* having a spindle *e*¹ journaled in the end walls *b*¹ *b*¹; and over these rollers *d* *e* which are parallel to one another, I provide an 80 endless apron *f* of flexible material such as rubberized canvas or the like. This apron *f*, the upper and lower runs of which are shown in dotted lines in Figures 1 and 2, is wholly secured inside the frame *a* *b* by means of the rollers *d* *e*, and is of such a length that between the rollers *d* and *e* it can sag or droop to form a trough. When the frame is opened (Fig. 1), tobacco can be inserted 85 in the trough between the parallel rollers *d* *e*, and the charge of tobacco rolled to a cylindrical shape by a to-and-fro motion of the endless apron *f* when the frame has been closed up (Fig. 2). The cigarette paper, in 90 which the cylindrical charge is to be wrapped, is then introduced into the casing and this outer paper covering is secured in position in the well known manner.

The end walls *a*¹ *a*¹ *b*¹ *b*¹ are shown in 100

Figs. 1, 2, 3 and 4 with flanges g g , which abut when the frame a b is closed up. These flanges form stops for the end walls a^1 and b^1 .

Now according to the present invention 5 and to prevent any part of the charge of tobacco from escaping over the lateral edges of the endless apron adjacent to the flanges g g or otherwise, I provide at each end of the frames a b and inside the end walls a^1 b^1 , 10 cover plates or cheek plates such as h h . In Figs. 1 to 4, these cover plates h h (one of which is shown separately in Fig. 5) are loose members mounted upon the pins or axles d^1 e^1 of the rollers around which the 15 endless apron f passes, and as clearly shown in Figs. 1 and 3, these cover plates h h are located inside the frame itself. Each cover plate is provided with ended slots h^1 for the pins or axles d^1 e^1 at the end of the frame- 20 halves, and these two slots h^1 h^1 in each cover plate h are curved to the centre of the hinge c in the frame or casing. Thus the pins or axles d^1 e^1 at each end of the hinged or pivoted frame a b can travel freely along 25 the curved slots h^1 h^1 in the cover plate h at that end.

The cover plate h may at its upper edge extend flush with the edges of the frame a b remote from the hinge c when the frame is 30 closed, and at the lower edge extend almost to the hinge c , as will be clear from Fig. 2. The pins d^1 e^1 move freely in the slots h^1 h^1 and the cover plates h h remain substantially at right angles to the hinge-axis c of the 35 frame a b , so as to prevent the charge of tobacco from escaping over the lateral edges of the apron f .

An additional advantage provided by 40 these cover plates is that the machine is not limited to shredded tobacco but can work quite satisfactorily with a proportion of tobacco "dust", or with tobacco of the kind which is poured from a packet.

The slots h^1 h^1 also act to limit the outward movement of the hinged halves of the frame or casing a b so that no undue strain 45 can be put on the endless apron f and a shallow trough or a deeper trough is at all times maintained, whether the frame or casing be 50 open or closed.

The slots h^1 in the cover-plates or end-pieces h are so arranged that the movement of the spindles d^1 e^1 therein is limited in order that the rollers d e cannot come so close 55 together, when the casing is closed, that they exert pressure against one another. If the two rollers could be pressed against each other to such an extent that one bears against 60 the other (even with the interposed apron), the rollers would rotate in opposite directions whereas in the rolling of a cigarette in the apron-trough, the rollers should rotate in the same direction. The slots h^1 h^1 are 65 therefore cut of such a length at their inner

ends that they keep the rollers apart even if the casing is squeezed too hard in use, and there is no need to open the casing a second time to feed the cigarette paper around the rolled charge of tobacco. The leading edge 70 of the paper can in fact be introduced without opening the closed up casing.

The cover plates h h are thus provided with means for limiting the outward movement of the casing when the latter is being opened and 75 with means for preventing the rollers from being pressed one against the other when the casing is closed up.

In another form, see Figures 6 and 7, each of the cover plates or cheek plates h is connected integrally with one of the halves a or b of the hinged frame or casing so as to move therewith and to overlap the end wall on the other half of the frame or casing upon the inner side. These two integral cover plates are arranged to project in opposite directions, as shown in Fig. 7. Where the cover plate overlaps the end wall on the other half of the frame, it may be slotted with a curved slot h^1 in which travels the pin or axis 85 of the roller in that half of the frame or casing, so that the opening movement of the casing or frame is limited in extent. The slots h^1 are of such a length that they prevent the rollers d e from pressing against one another 90 when the casing is closed up, for the reason above explained.

The longer walls of the frame or casing carrying these cover plates for the roll-forming trough may be ribbed, as shown at i in Figure 4, to stiffen the walls and to prevent the said walls from being dented or crushed when, for instance, the machine is carried in the pocket. It will also be noted from Fig. 4 that the end walls a^1 b^1 carrying the hinge pin c extend below the side walls of the frame or casing and act as feet or supports when the frame is to be placed upon a table or the like.

A cigarette rolled in this machine provided with cover plates is evenly packed right up to the ends, as if the ends had been neatly trimmed. There is a saving in tobacco because losses due to an open end of the trough are avoided. Further by reason of the limiting slots in the cover plates, the halves a b cannot be opened so far apart as to strain the endless apron f , and on the other hand the rollers d e are prevented from pressing one against the other when the casing is closed up.

What I claim is:

1. A hand operated cigarette-making machine, comprising, a casing with two hinged halves, a roller journaled in each of said halves of the casing, an endless apron passing around said rollers and adapted to form a trough between the rollers for the rolling of the cigarette, and closure members, slidably connected with at least one of said halves at 110

either end of said casing substantially at right angles to the hinge axis thereof, adjacent the edges of the endless apron, for the purpose described.

- 5 2. A hand operated cigarette-making machine, comprising, a casing with two hinged halves, a roller journaled in each of said halves of the casing, an endless apron passing around said rollers and adapted to form a trough between the rollers for the rolling of the cigarette, and closure members, slidably connected with at least one of said halves at either end of said casing substantially at right angles to the hinge axis thereof, adjacent the edges of the endless apron, together with means, carried by said closure members, for limiting the opening and closing movements of the hinged halves of the casing, for the purposes described.
- 10 3. A hand operated cigarette-making machine, comprising, a casing with two hinged halves, a roller journaled in each of said halves of the casing, an endless apron passing around said rollers and adapted to form a trough between the rollers for the rolling of the cigarette, and cover plates, slidably mounted against the inner sides of the end walls of at least one of said halves, at either end of the casing substantially at right angles to the hinge axis of the casing, adjacent the edges of the endless apron.
- 15 4. A hand operated cigarette-making machine, comprising, a casing with two hinged halves, a spindle mounted in each of said halves of the casing, a roller carried by each spindle an endless apron passing around said rollers and adapted to form a trough between the rollers for the rolling of the cigarette, and cover plates, located against the inner sides of the end walls of the casing and each provided with two slots having closed ends and curved to the centre of the hinge of the halves of the casing, said spindles being inserted in said slots.
- 20 5. A hand operated cigarette-making machine, comprising, a casing with two hinged halves, a roller journaled in each of said halves of the casing, an endless apron passing around said rollers and adapted to form a trough between the rollers for the rolling of the cigarette, and closure members slidably connected with at least one of said halves at either end of said casing substantially at right angles to the hinge axis thereof, adjacent the edges of the endless apron, together with stiffening ribs in the longer walls of the hinged casing.
- 25 6. A hand operated cigarette-making machine, comprising, a casing with two hinged halves, a roller journaled in each of said halves of the casing, an endless apron passing around said rollers and adapted to form a trough between the rollers for the rolling of the cigarette, and a cover plate, integral with one of the halves of the casing, at each end of

said casing, and adapted to overlap the other half of the same when in the closed position.

In testimony whereof I have signed my name to this specification.

RICHARD NORMAN BOOTH.
